UNITED STATES PATENT OFFICE

ALFRED W. BRUCE, OF NEW YORK, N. Y.

LOCOMOTIVE

Application filed October 20, 1930. Serial No. 489,827.

This invention relates generally to locomotives and more particularly to locomotives designed to work under high steam pressures.

3 The locomotives used in general practice have heretofore comprised a boiler with a stay bolt shell portion surrounding the fire box and the combustion chamber and a cylindrical shell extending forwardly therefrom 10 containing fire tubes. In such locomotives a steam pressure has been used of approximately 200 lbs. It has been found, however, that a material economy in both fuel and water may be effected by the use of high 15 single pressure steam, for example, 500 lbs. With such use a maximum efficiency and economy may be achieved by effecting a positive circulation through the pipes and drums in transverse planes. This arrangement affords the shortest possible length for 20 a complete water circuit, at the same time obviating interference in the different water circuits.

In my prior co-pending application Serial Number 385,654, filed August 13, 1929 25 for improvements in high pressure locomotives, I have exemplified a high pressure steam generator in which circulation pipes and drums are so arranged in the fire box 30 and combustion chamber as to effect the aforesaid transverse circulation throughout the length of the same.

An object of the present invention is to 35 provide a locomotive which is designed for the use of high pressure steam in which the advantages of transverse circulation may be realized in the forward barrel portion of the same as well as in the fire box and combustion chamber, while at the same time retaining a boiler design suitable for use on locomotives following the present day practice.

40 A further object of the invention is to provide a locomotive with the aforesaid characteristics embodying a construction which will have the advantage of simplicity and ruggedness while at the same time being adaptable for any desired wheel arrangement.

45 A further object of the invention is to pro-

vide a structure such as the aforesaid which will employ minimum size steam and water drums so arranged as to afford a maximum steam space while at the same time being able to collect steam from chambers where 55 there is no direct ebullition.

A further object of the invention is to provide a locomotive of the aforescribed type in which the forward section may be formed integrally with or separately from the fire 60 box section, as may be desired, and said sections will be so positioned that the same water level will be maintained in both, thus permitting a single water feed attachment for the same.

65 In the accompanying drawings, Fig. 1 is a side elevation of a locomotive with the boiler and fire box jackets removed showing this invention applied thereto; Fig. 2 is a plan view of the same; Fig. 3 is a sectional view taken 70 on the line III—III of Fig. 1; Fig. 4 is a sectional view taken on the line IV—IV of Fig. 1; Fig. 5 is a diagrammatic view showing, on the left hand side, the circulation through the fire box and, on the right hand 75 side, the circulation through the barrel portion; Fig. 6 is a back view on an enlarged scale of the structure illustrated in Fig. 1; and Fig. 7 is an isometric view on an enlarged scale of the central header and parts of cer- 80 tain of its attendant elements.

In the practice of the invention, referring descriptively to the specific embodiment thereof which has been selected for exemplification herein, the locomotive comprises a 85 forward fire tube section 10 and a rear fire box section 11. It will be understood that throughout the specification and claims where the words fire box or fire box section are used, the same are intended, unless otherwise specified, to include the fire box section alone of those locomotives which do not include a combustion chamber section, and to include both the fire box and the combustion chamber sections of those locomotives which 95 have a combustion chamber between the fire box and the fire tube section.

The fire box section comprises two bottom water drums, 12, the rear half of a central upper steam drum 13, which extends the length 100

of both the fire box section and the fire tube section and the rear half of two outer upper steam drums, 14, which likewise extend the length of both the fire box section and fire tube section one disposed on each side of the steam drum and parallel therewith. Within the fire box, upflow circulation pipes 15, connect the bottom drums 12 with the central upper drum 13 and downflow circulation pipes 16, connect the outer upper drums 14 with the bottom drums 12; the combustion chamber 17 being within the upflow pipes. A rear header 18 (Fig. 6) is provided at the end of the drums, and a fuel door 19 is formed therein. The header is connected with the lower drums 12 and the upper central drum 13. Cross pipes 20 connect the outer steam drums 14 with the central drum 13. The upflow pipes 15, each have a lower substantially vertical portion at the side of the fire box and an upper diagonal portion which overlies the top of the fire box. These upflow pipes are arranged in rows or banks and so spaced and staggered with relation to each other as to afford the greatest possible exposed surface and to cause the gases of combustion to travel around them in a tortuous path, thus obtaining a maximum thermal efficiency from the gases.

The forward part or fire tube section of the generator, comprises a main cylindrical barrel 21 of relatively large diameter, having fire tubes 22 arranged within the same passing longitudinally therethrough. The forward half of the upper central steam drum 13, which drum, as hereinbefore stated, extends the length of both the fire box section and fire tube section, passes above the barrel 21, parallel therewith and is connected to the same by vertical passageways 23. Likewise the forward half of the outer upper drums 14, which drums, as aforesaid, extend the length of both the fire box section and fire tube section, are disposed above the barrel one on each side of the central drum, and parallel therewith as aforesaid and are connected to the central drum 13 by horizontal passageways 24. A longitudinal drum 25 is located centrally below the barrel 21, parallel with the same. Downflow pipes 26, are connected to the bottom of the upper outer drums 14, and have upper substantially vertical portions which extend downwardly along the sides of the barrel, and lower diagonal portions which pass under the barrel, their lower ends being connected with the drum 25. Vertical passageways 27 connect the lower drum 25 with the barrel 21.

A central header 28 (Fig. 7) is disposed between the forward section 10 and the fire box section 11. The central upper drum 13 passes through the header which serves to hold it in its proper relative position.

It will of course, be noted that the central drums as well as the outer upper drums 14

may be either single continuous integral members as described or may comprise two separate drums suitably connected together. The header 28 is of such shape that the outer upper drums 14 pass on the outside of the same, and are not in contact therewith.

The lower drums 12 are connected at their forward ends to the header 28 and are held in position thereby. The header serves as a rear tube sheet for the barrel 21, and the upper central drum 13, and the lower fire box drums 12 are provided with openings in their sides within the header, (as shown in Figs. 3 and 7), so that the header establishes communication between the barrel, the upper central drum and the lower fire box drums. The water passes from the forward section to the fire box section through the rearmost downflow pipes 26' which are connected to the lower water drums 12. The boiler feed is introduced into the lower central drum 25 of the forward section by a pipe 29 connected thereto.

A superheater 30 of any preferred or usual design is provided as indicated in Fig. 1 and in the usual way it is connected at the front of the forward section 10 to a header 31, and has reaches 32 extending into the fire tubes 22.

The operation of the improved locomotive is as follows: Feed water enters the lower central drum 25 from the pipe 29 and passing through the upward passageways 27 circulates upwardly around the fire tubes 22 when heated thereby, continuing upwardly through the passageways 23 into the central upper drum 13 it passes outwardly through the passageways 24 to the outer upper drums 14 and then downwardly through the vertical pipes 26 back to the lower central drum 25, thus completing the transverse circulation through the forward section of the generator. As the water passes from the front of the forward section back to the rear of the same the sediment therein is precipitated in a decreasing amount from front to back, so that only a very small amount will reach the fire box section. Passing from the downflow tubes, 26' the water enters the lower drums 12 of the fire box section. Here a similar transverse circulation is effected, the water passing upward through the tubes 15 to the upper central drum 13 through the passageways 20 into the outer drums 14, and then downwardly through the outer tubes 16 back into the lower drums 12. It will thus be noted that the water circulates positively in transverse planes throughout the entire length of both the fire box section and the forward barrel portion of the locomotive. As the most violent ebullition in both sections, occurs in the central upper drum 13 the steam is withdrawn from the outer upper drums 14 where a condition of relative quiescence exists and the steam is relatively dry. The use of three drums also has an advantage of providing

and connecting means between a receiving member for the downflow units of the fire box section and a downflow unit of the fire tube section.

- 5 10. A locomotive steam generator comprising a rear fire box section, and a forward fire tube section, both of said sections comprising a downflow and upflow unit arranged to effect the circulation of water therethrough 10 transversely of said fire tubes in a vertical direction, a receiving member for the upflow units of both sections comprising a single continuous passage longitudinally across both of said sections connected with said 15 upflow units, receiving members for the downflow units of each of said sections connected with said downflow units, and connecting means between a downflow receiving member of the fire box section and a 20 downflow unit of the fire tube section.

11. A locomotive steam generator comprising a rear water tube fire box section, and a forward fire tube section, both of said sections having a downflow unit and an upflow 25 unit for the circulation of water therethrough in transverse planes, and a header disposed between said sections connecting the same and establishing communication therebetween.

- 30 12. A locomotive steam generator comprising a rear water tube fire box section, and a forward fire tube section, both of said sections having a downflow unit and an upflow unit, a receiving member for the upflow units 35 of both sections connected thereto, and separate receiving members for the downflow units of each of said sections respectively connected thereto, arranged to effect the circulation of water therethrough in transverse 40 planes, the receiving member for the upflow units of both of said sections comprising a single continuous member extending the length of both of said sections, and a header disposed between said sections and providing 45 connecting means for said sections and establishing communication therebetween.

13. A steam generator for a locomotive comprising a rear fire box section, and a forward fire tube section, both of said sections 50 having upflow and downflow units, receiving members for the upflow units of said sections, and receiving members for the downflow units of said sections, the said receiving members for the upflow units of both sections 55 being disposed with relation to each other so as to effect a common water level.

14. In a locomotive, a steam generator comprising a barrel member having fire tubes passing therethrough, a drum disposed above 60 said barrel member, a water drum disposed below said barrel member, a row of downflow tubes effecting communication between the upper drum and the lower drum, and connecting passages between the barrel member 65 and the upper and lower water drums, to

effect the circulation of water through said generator in opposite directions in substantially vertical transverse planes, the said barrel member constituting the upflow passage of said circulation. 70

15. A steam generator for locomotives comprising a barrel member having fire tubes passing therethrough, a bottom water drum, disposed below said barrel member, a central upper steam drum, disposed above said barrel member, connecting passages between said barrel member and said bottom drum and said upper drum, an outer upper steam drum arranged parallel with said central drum, a passage establishing communication between 80 said outer drum and said central drum, and a row of downflow pipes connecting said bottom drum with said outer upper steam drum. 85

16. A locomotive steam generator comprising a rear fire box section, and a forward fire tube section connected thereto, said forward section comprising a barrel member having fire tubes passing therethrough, a bottom water drum disposed below said barrel member, means connecting said bottom water drum to said barrel member and establishing communication therebetween, a central upper steam drum disposed above said barrel member, means connecting said central upper steam drum with said barrel member and establishing communication therebetween, an outer upper steam drum arranged parallel with said central drum, a passage establishing communication between 90 the outer steam drum and the central steam drum, downflow pipes connecting the bottom drum with the outer upper steam drum, the said central upper steam drum extending to and communicating directly with the said fire box section, and means disposed between 95 the two sections for effecting communication between downflow pipes of the forward section and the said fire box section. 100

17. In a locomotive, a steam generator comprising a rear fire box section comprising a lower water drum, an upper steam drum, a row of upflow pipes leading to the upper drum and a row of downflow pipes for returning water to the lower drum, and a forward fire tube section comprising a barrel member having fire tubes passing therethrough, a lower water drum disposed beneath said barrel member parallel therewith, means connecting said lower water drum with said barrel member and establishing communication 115 therebetween, an upper central steam drum, disposed above said barrel member parallel therewith, means connecting said upper central steam drum with said barrel member and establishing communication 120 therebetween, an upper central steam drum, disposed above said barrel member parallel therewith, means connecting said upper central steam drum with said barrel member and establishing communication 125 therebetween, and a row of downflow tubes for returning water from said upper drum to said lower drum, the said upper steam drums of both sections being connected to form one continuous passageway, and means disposed between 130

ample surfaces for steaming and a maximum volume for storage. The steam is carried in the usual manner through the dry pipes 33 to the super-heater header 31 and so 5 on through the super-heater.

It will be noted that in the arrangement aforescribed the fire box and barrel sections are adapted to be installed or removed from the locomotives as one complete unit or 10 if desired may be constructed in two separate sections. The invention thus provides a high pressure locomotive which is both simple and rugged in construction, that is economical to manufacture and maintain, and which affords 15 a highly efficient apparatus in that a material saving in fuel and water may be effected by the use of the same.

While there has been hereinbefore described and illustrated one of the preferred forms 20 of construction of the invention it will be apparent that many and various changes and modifications in procedure, form, arrangement, and construction of same may be resorted to and, that the invention is not limited, therefore, to this particular embodiment disclosed, but includes all such changes and modifications as come within the spirit and scope of the same as defined in the appended 25 claims.

30 The invention claimed and desired to be secured by Letters Patent is:

1. In a locomotive, a steam generator comprising a barrel having fire tubes passing longitudinally therethrough, and means disposed outside of said barrel and connected thereto to effect the circulation of water through said barrel transversely of said fire tubes in a vertical direction.

2. In a locomotive, a steam generator comprising a barrel having fire tubes passing longitudinally therethrough, and a plurality of water tubes associated therewith to effect the circulation of the water through said barrel transversely of said fire tubes in a vertical 45 direction.

3. In a locomotive, a steam generator comprising a water tube fire box section, and a forward fire tube section, said fire tube section comprising a barrel having fire tubes 50 passing longitudinally therethrough and a plurality of water tubes outside of said barrel and connected thereto, arranged to effect the circulation of water through the forward section transversely of said fire tubes in a vertical direction.

4. A locomotive steam generator comprising a water tube fire box section, and a forward fire tube section, said fire box section comprising means for circulating water 60 therethrough in opposite directions in substantially vertical transverse planes, and said fire tube section comprising a barrel having a plurality of fire tubes passing longitudinally therethrough and means disposed outside of said barrel and connected thereto

to effect the circulation of water through said section in opposite directions in substantially vertical transverse planes.

5. In a locomotive, a steam generator comprising a barrel having fire tubes passing therethrough, an upper steam drum above said barrel, a lower water drum below said barrel, connecting passageways between said drums and said barrel, and independent connecting means between the said drums, for effecting the circulation of water through said generator in opposite directions in substantially vertical transverse planes.

6. In a locomotive, a steam generator comprising a plurality of cylinder members positioned in at least three different horizontal planes, a cylinder of the middle plane having fire tubes passing horizontally therethrough, connecting passageways between the fire tube cylinder and cylinders of the other planes, and a plurality of substantially vertical tubes connecting said upper and lower cylinders, to effect the circulation of water through said generator transversely of said fire tube cylinder in a vertical direction, said fire tube cylinder constituting an upflow passage and said tubes constituting downflow passages.

7. In a locomotive, a steam generator comprising a rear fire box section, and a forward fire tube section, said fire tube section comprising a plurality of cylinder members positioned in at least three different horizontal planes, a cylinder of the middle plane having a plurality of fire tubes passing longitudinally therethrough, connecting passageways between the fire tube cylinder and the cylinders of the other planes, and a plurality of substantially vertical water tubes independently connecting the upper and lower cylinders arranged to effect the circulation of water through said fire tube cylinder and water tubes in opposite directions in substantially vertical planes transversely of said fire tubes.

8. A locomotive steam generator comprising a rear water tube fire box section, and a forward fire tube section, both of said sections having downflow and upflow units arranged to effect the circulation of water therethrough transversely of said fire tubes in a vertical direction and a receiver for their upflow units comprising a single continuous member extending the length of both sections.

9. A locomotive steam generator comprising a rear fire box section, and a forward fire tube section, both of said sections comprising downflow and upflow units arranged to effect the circulation of water therethrough transversely of said fire tubes in a vertical direction, a receiving member for the downflow units of the rear section, connected thereto, a receiving member for the downflow units of the forward section, connected thereto,

the two sections for effecting communication between the said downflow tubes of the forward section and the said lower drum of the fire box section, whereby water will be circulated through both of said sections in transverse planes.

18. In a locomotive, a steam generator comprising a forward fire tube section, and a rear fire box section, a longitudinally and centrally disposed upper steam drum extending the length of both of said sections, a longitudinally disposed upper steam drum at the outside of said centrally disposed steam drum extending the length of both of said sections, means connecting said outer drum and said central drum, lower water drums for both of said sections, downflow and upflow pipes for the said fire box section between the said upper and lower drums connecting the same, downflow pipes between the outer upper and the lower drums of said fire tube section, a barrel member containing fire tubes disposed between said upper and lower drums of said fire tube section, means connecting said barrel member with said central upper drum and said lower drum of the forward section, said barrel member constituting an upflow passage for said forward section, and a header disposed between the two sections, the said upper central steam drum passing therethrough and the said lower water drums of the fire box section and the barrel member of the fire tube section being connected to said header, and at least one of the downflow pipes of the forward section being in communication with a lower water drum of the fire box section, whereby water will be circulated through both of the said sections in substantially vertical transverse planes.

40 ALFRED W. BRUCE.
